UNITED STATES PATENT OFFICE

2,607,349

DIAPER HOLDER

Mildred L. Biancavilla, Syracuse, N. Y.

Application October 17, 1950, Serial No. 190,545

1 Claim. (Cl. 128—287)

1

This invention relates to new and useful improvements and structural refinements in infant garments, and the principal object of the invention is to provide a garment of the character hereindescribed, which may be conveniently and effectively employed for holding diapers in position on the infant's body, this being accomplished without the use of conventional diaper pins, or the like.

Primarily, the invention contemplates the provision of a holder which is formed from waterproof material and is adapted to receive an absorbent diaper therein, some of the advantages of the invention residing in its simplicity of construction, in its efficient and expeditious operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a rear perspective view of the invention;

Figure 2 is a developed plan view thereof;

Figure 3 is an enlarged sectional detail, taken substantially in the plane of the line 3—3 in Figure 2; and

Figure 4 is an enlarged sectional detail, taken substantially in the plane of the line 4—4 in Figure 2.

Like characters of reference are employed to designate like parts in the specification and throughout the several views.

Referring now to the accompanying drawings in detail, the invention consists of a diaper holder which is designated generally by the reference character 10 and embodies in its construction an elongated sheet 12 of flexible, waterproof material, which sheet is provided with a relatively narrow intermediate region 14 so that when the sheet is folded transversely, the region 12 affords a crotch portion and regions of the sheet forwardly and backwardly of the crotch portion constitute front and back walls 16, 18, respectively.

The relatively wide upper edge portions of the walls 16, 18 are overlapped and preferably attached together at the opposite sides of the garment so as to coact with the crotch portion 14 in defining a pair of leg openings, one of the latter being indicated at 20 in Figure 1.

End portions 22, 24 of the sheet 12 are turned

inwardly and downwardly from upper edges of the respective front and back walls 16, 18 and continuous binding 26 is applied to top and side edges of the two walls, so that the end portions 22, 24 coact with the respective walls 16, 18 in defining front and rear pockets 28, 30. When the invention is placed in use, end portions of an absorbent diaper 32 may be inserted in these pockets, as indicated in Figure 2, whereby the diaper will be effectively supported by the holder.

A pair of pull tabs 34, assuming the form of doubled strips of suitable material, are secured to the outer surface at the opposite sides of the upper edge portion of the rear wall 18 by conventional snap fastener elements 36, while similar pull tabs 38 are secured by coacting snap fastener elements 40 to opposite sides of the upper edge portion of the front wall 16.

The pull tabs 34, 38 not only facilitate application and removal of the garment, but also reinforce the garment at points of fastening. The fastening operation is accomplished by simply overlapping the relatively wide upper edge portions of the walls 16, 18 at the opposite sides of the garment and then engaging the snap fastener elements 36 with either pair of the snap fastener elements 40, whereby the holder as well as the diaper therein will be dependably sustained in position on the body of an infant without the use of conventional pins. By employing several sets of the fastener elements 40, the holder may be adjusted so as to accommodate infants of different sizes.

If desired the back wall 18 may be provided with pleats 42 to assure proper fit, and it is to be noted that the folded portions 22, 24 of the sheet 12 have arcuate lower edges 44 to assist in centralizing the diaper 32 in the pockets 28, 30 and prevent the diaper from slipping.

It is believed that the advantages and use of the invention will be clearly understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

55 A diaper holder comprising an elongated sheet

of flexible waterproof material having a relatively narrow intermediate region folded transversely to afford a crotch portion and front and back walls with relatively wide upper edge portions which are overlapped and separably attached together at the opposite sides of the holder for coaction with said crotch portion in defining a pair of leg openings, end portions of said sheet being turned inwardly and downwardly from upper edges of the respective front and back walls and secured at the side edges thereof to the corresponding side edge portions of the front and back walls whereby to provide inverted pockets adapted to receive end portions of an absorbent diaper inserted in said holder, combined reenforcing and pull tabs provided on said overlapped portions of said front and back walls and each comprising a flexible strip doubled upon itself and having its end portions superposed on the associated wall, an intermediate portion of said strip constituting a loop project-

ing upwardly beyond the upper edge of the associated wall, and coacting snap fastener elements secured to said holder and to said end portions of said strips, whereby the overlapped portions of said walls may be connected together.

MILDRED L. BIANCAVILLA.
